(57) **CLAIM**

The ornamental design for an architectural panel with line and bunch interlayer design, as shown and described.

DESCRIPTION

FIG. 1 is a front perspective view of an architectural panel with line and bunch interlayer;

FIG. 2 is an enlarged front perspective view thereof;

FIG. 3 is a left side elevation view taken along line 3-3 of FIG.

4

FIG. 4 is a front elevation view thereof;

FIG. 5 is a right side elevation view taken along line 5-5 of FIG. 4;

FIG. 6 is a bottom plan view taken along line 6-6 of FIG. 4;

FIG. 7 is a top plan view taken along line 7-7 of FIG. 4; and,

FIG. 8 is a back elevational view thereof.

The broken lines showing environment in the drawings are included for illustrative purposes only and form no part of the claimed design. The outer broken line boundaries in Figures depicting the boundaries of the claimed design indicate that a specific length, width, and thickness form no part of the claimed design and are for illustrative purposes only.
